US00D876237S

(12) **United States Design Patent** (10) Patent No.: **US D876,237 S**
(45) Date of Patent: **** Feb. 25, 2020**

(54) **CAP FOR A CONTAINER**

(71) Applicant: **3M INNOVATIVE PROPERTIES COMPANY**, St. Paul, MN (US)

(72) Inventors: **Michael J. Rust**, Volga, SD (US);
Patrick R. McKellips, Stillwater, MN (US)

(73) Assignee: **3M Innovative Properties Company**, St. Paul, MN (US)

(**) Term: **15 Years**

(21) Appl. No.: **29/670,436**

(22) Filed: **Nov. 15, 2018**

Related U.S. Application Data

(62) Division of application No. 29/627,060, filed on Nov. 22, 2017, now Pat. No. Des. 838,166, which is a division of application No. 29/572,732, filed on Jul. 29, 2016, now Pat. No. Des. 812,474.

(57) **CLAIM**

The ornamental design for a cap for a container, as shown and described.

DESCRIPTION

FIG. 1 is a perspective view of a cap for a container showing our new design;

FIG. 2 is a front elevational view thereof;

FIG. 3 is a rear elevational view thereof;

FIG. 4 is a left side elevational view thereof and the right side elevational view being a mirror image thereof;

FIG. 5 is a top plan view thereof;

FIG. 6 is a bottom plan elevational view thereof; and,

FIG. 7 is a perspective view of the cap for a container in use.

(Continued)

In the drawings, the broken lines showing portions of a cap and container depict environment and form no part of the claim.

1 Claim, 4 Drawing Sheets
